UNITED STATES PATENT OFFICE.

WILLEM PETRUS MULIÉ, OF LEYDEN, NETHERLANDS, AND BENJAMIN HYMANS VAN DEN BERG, OF ANTWERP, BELGIUM.

LIFE-BOAT.

SPECIFICATION forming part of Letters Patent No. 642,622, dated February 6, 1900.

Application filed December 5, 1898. Serial No. 698,350. (No model.)

To all whom it may concern:

Be it known that we, WILLEM PETRUS MULIÉ, a subject of Her Majesty the Queen of Holland, residing at Leyden, in the Kingdom of the Netherlands, and BENJAMIN HYMANS VAN DEN BERG, a subject of His Majesty the King of Belgium, residing at Antwerp, in the Kingdom of Belgium, have invented a new and useful Life-Boat, (for which we have obtained provisional protection in Great Britain, No. 23,314, bearing date November 5, 1898, while a patent has also been applied for in Germany, dated November 8, 1898, and in France, Serial No. 270,634, dated November 8, 1898,) of which the following is a specification.

The present invention relates to an improved life-boat for sea-going vessels and the like, which boat is absolutely secured against upsetting, but which when in the folded condition does not take up more room than an ordinary ship's boat.

Ships' boats of the usual kind, in which the passengers in case of shipwreck endeavor to save their lives, lose much of their value because in the case of storms and rough sea the danger of upsetting is very great, and this also often occurs when in the panic the passengers press to one side of the boat. Consequently these boats deserve the name of life-boats only partially, because their safety is not by any means assured.

The object of the present invention consists of a boat especially for sea-going ships, which in reality deserves the name of a life-boat, because it not only possesses all the advantages which the present boats possess, but, in addition to this, it possesses an arrangement whereby the upsetting or sinking is practically made impossible, even under the most unfavorable circumstances. This arrangement, which forms the subject of the present application for a patent, is carried in the inside of the boat while the same is out of use, and thereby the dimensions of a boat of this kind are rendered no greater than those of an ordinary ship's boat. In case of emergency the device is capable of being made serviceable in a very simple way. It essentially consists of cylindrical hollow vessels of sheet-iron made water-tight and divided

into compartments by water-tight divisions. These cylinders possess a great buoyancy and are fixed to long supports, which effect the connection with the boat. These floating out-riggers, connected by a long leverage, form a support which resists the capsizing of the boat.

The invention is illustrated in the accompanying drawings in connection with a boat which itself is devised to comply with the requirements which may be made in the case of a life-boat.

In the drawings, Figure 1 represents a longitudinal section; Fig. 2, a transverse section; Fig. 3, a plan view, and Figs. 4 to 6 various details on a larger scale. Fig. 7 shows, on an enlarged scale, the locking mechanism securing the supports of the float to the side of the boat.

The boat R is provided in the well-known manner with a double bottom, and the intermediate space is filled with water-tight cylinders M. Over this double bottom, at each side, are placed the lockers K, which act at the same time as seats and as water-tight compartments for containing tools and food. The cisterns H are filled with oil, which can be discharged through the tubes I and serve in case of need to render the water smooth in the neighborhood of the boat. In the bottom of the boat are placed the tubes G, Figs. 2, 3, and 6, through which any water coming on board can flow out and which are provided with back-pressure valves to prevent any water flowing in from the outside. Three strong bars D are secured at each side of the boat, which terminate at the gunwale in hinges. Upon these hinges the supports B revolve, which supports B connect the hollow cylinders A with the boat by aid of the connecting-bars S, which serve to hold the cylinders A in their place and to strengthen the aforesaid bars B. The cylindrical hollow bodies A are divided by means of water-tight partitions into compartments, and they terminate in front and behind in pointed ends. The supports B are connected by means of the tie-rods F.

N indicates a handle for the purpose of bringing the cylinders inboard. In Figs. 2 and 3 the position of the cylinders A when the boat is out of use is indicated by dotted

lines. In this position the boat hangs in the davits and occupies no more room than an ordinary ship's boat. It will be obvious that the supports B in this position of the cylinders A are able to occupy spaces left between the lockers K. When it is desired to make use of the boat as a life-boat, the cylinders A are turned overboard into the position shown in full lines in Fig. 3 and the supports B locked 5 at E. The boat can then be lowered into the water. The hollow water-tight cylinders A possess a very great buoyancy, which, being placed on the long leverage of the supports B, gives a stability which renders the capsizing 10 of the boat almost impossible. Owing to 15 its very great buoyancy the danger of the boat sinking is also almost excluded. The division of the cylinders into water-tight compartments causes in the case of an injury 20 that the same is limited to the compartment actually damaged and prevents the water passing into the remainder of the cylinder. The tapering form in front and behind aids the progress of the boat in the water through 25 the diminished resistance. The bars F and C serve also as hand-rails—the bars F for the support of persons who may have fallen into the water and the bars C, which form the axle on which the cylinder-supports revolve, serve 30 also as rails for the boat.

The lower connection between the supports B and the side of the boat can be disengaged or secured from inside the boat. The apparatus for this purpose (shown in detail in Fig. 35 7) consists, preferably, of a bolt E, which is placed horizontally with its bent outer end downward and passes through a horizontal slot at the lower end of the supports. Said bolt is revolved a quarter-turn, which releases the support. The bolt E is secured inside the boat by means of the cotter-pin e. 40

The bolt can, however, be secured by means of a wedge or the like in order to connect the support at E firmly with the rails D or the sides of the boat, or the bolting device may 45 act automatically by means of a spring-catch or the like locking the end of the bolt when inserted in the aperture of the bar D. At the front of the boat there is a device arranged for the rorer, for which purpose the row- 50 locks q are attached.

Q, Fig. 5, is an adjustable row-lock which can be placed at any convenient point, so that the boat may be steered also from the interior thereof, and the oars can reach over the 55 cylinders A in case of need.

What we claim is—

1. In a life-boat, hollow buoyant cylinders parallel to the sides of the boat, horizontal rails on the gunwales of said boat, supporting-arms pivoted on said rails and rigidly attached to said cylinders, locking devices for 60 said arms on the outside of the boat, and a lever-handle operated from the interior of the boat for raising the said cylinders and bringing 65 them into the interior of the boat.

2. In a life-boat, in combination adjustable floats A, supporting-bars D secured to the boat, horizontal rails C supported by said bars, duplex connecting-bars B attached to 70 the floats, and pivoted at their upper inward ends to the rail C, transverse supports S between the bars B, a handle N, and outer locking devices E engaging with the lower inward ends of the bars B. 75

In witness whereof we have hereunto set our hands in presence of two witnesses.

WILLEM PETRUS MULIÉ.

BENJAMIN HYMANS VAN DEN BERG.
